UNITED STATES PATENT OFFICE.

ALBERT DE LAUTREPPE AND HENRY MOLLET MESRINES, OF NEW YORK, N. Y.

DESIGN FOR A MEDAL.

55,027.

Specification for Design.

Patented May 4, 1920.

Application filed June 30, 1919. Serial No. 307,864. Term of patent 3½ years.

To all whom it may concern:

Be it known that we, ALBERT DE LAUTREPPE and HENRY MOLLET MESRINES, citizens of France, residing at New York, borough of Manhattan, in the county and State of New York, have invented a new, original, and ornamental Design for a Medal, of which the following is a specification, reference being had to the accompanying drawings, forming part thereof.

Figure 1 is a front view of our medal showing our new design.

Fig. 2 is a rear view thereof.

We claim:

The ornamental design for a medal, as shown.

ALBERT DE LAUTREPPE.
HENRY MOLLET MESRINES.
